(57) **CLAIM**

The ornamental design for a food processor accessory case, as shown and described.

DESCRIPTIONFIG. 1 is a top, front and right side perspective view of an accessory case showing my new design;
FIG. 2 a bottom, rear, and right side perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 illustrates the accessory case in an open position as seen from the top, front and right side perspective view thereof.

Broken lines illustrate environmental structure. The broken lines in the drawings are included for illustrative purposes only and form no part of the claimed design.
